ATTORNEY

UNITED STATES PATENT OFFICE.

ISAAC SNOW, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed December 26, 1924. Serial No. 758,064.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to looms and more particularly to feeler mechanisms whereby when the filling in the shuttle has become substantially exhausted, the operative condition of the loom is changed. This change in the operative condition of the loom may result in either loom stoppage or filling replenishment, and in the present instance it will be shown and described in connection with a train of mechanism for replenishing the filling in the shuttle when the feeler detects substantial exhaustion on a detecting beat.

Inasmuch as the function of the feeler mechanism is to change the operative condition of the loom when the filling is substantially exhausted on a detecting beat, the present invention contemplates means for holding the feeler in an inactive position for periods of time and then permitting the feeler to discharge its feeling function during one or more detecting beats and in case a working supply of filling is present in the shuttle to again hold the feeler inactive until, when the feeler detects a near approach to substantial exhaustion of filling, it will remain in action to call for a change of filling when that in the shuttle is substantially exhausted. Feeler mechanisms of this general type are now generally known as "intermittent feelers" because they have periods of activity alternating with periods of inactivity during weaving with the same supply of filling in the shuttle, thereby avoiding the recurring contacts of the feeler with the filling on each detecting beat until the critical period is approached.

In accordance with the present invention, the controlling means for the feeler is disposed back of the breast beam or shipper stand, which removes the controlling means from interference with the attendant's manipulation of the loom and permits the controlling means to be actuated from time

to time by a cam follower which may preferably take the form of the weft fork hammer, and inasmuch as the weft hammer or cam follower continues its operative movements during weaving, the controlling means, in accordance with the present invention, is constructed and arranged for non-actuation by the cam follower or weft hammer for periods of time, and to be then moved into the path of movement of the cam follower or weft hammer to periodically release the actuator to its feeling function.

The invention and new combination of parts will best be made clear from the following description and the accompanying drawings of one good form thereof, wherein the means for controlling the feeler is actuated from the cam shaft which has a one-to-two relative movement with the crank shaft.

In the drawings:

Fig. 1 is a perspective view of one end of a loom provided with the present invention.

Fig. 2 is a plan view with some of the parts broken away and showing the relation of the members of the feeler mechanism during weaving with a working supply of filling in the shuttle, the feeler at such times being held in its frontward or retracted position; and

Fig. 3 is a section on the line 3—3 of Fig. 2.

In the illustrated form of the invention, the feeler is shown as of the inclined type, substantially as disclosed in the patent to Edward S. Stimpson, No. 1,309,226, July 8, 1919, and while the advantages of the present invention are well-manifested in connection with this type of feeler mechanism, it is understood that it may be advantageously employed with other types.

The replenishing mechanism for furnishing the shuttle with a fresh supply of filling when the feeler detects substantial exhaustion of the filling in the shuttle, is not herein shown and described, because the details thereof form no part of the present invention and are now well understood by those familiar with filling replenishing looms.

The loom frame may be of usual construction, and in the present instance the breast beam has extending therefrom a ship-

per stand 1 having a slot 2 through which the shipper 3 extends, and so far as the present invention is concerned, the shipper stand may be regarded as part of the breast beam.

Mounted upon the loom frame is a train of mechanism for effecting replenishment of filling when the feeler detects substantial exhaustion thereof in the shuttle, such train of mechanism as shown comprising an arm 4 extending upwardly from the usual transverse or rock shaft (not shown) having pivotally connected thereto at 5 the rearwardly extending arm 6, the rear end portion of which has pivoted thereto at 7 a finger 8 the end portion 9 of which is adapted at times to be engaged by the cam follower 10 or a part associated therewith. The finger 8 has a projection 11 which overlies one arm 12 of a bell crank lever pivoted at 13 to a support 15 which may be conveniently secured to the breast beam or shipper stand by a bolt 16. The other arm 17 of the bell crank lever is connected to a transmitter 18 which is joined at 19 with a slide 20 through which the feeler 21 extends. The slide 20 is guided in its lateral movement by suitable guideways at the rear of the feeler stand as at 22, which may be conveniently formed as part of or connected to the feeler stand 23, and the feeler stand 23 may itself be adjustably connected to the shipper stand or an arm extending therefrom by a bracket 24, to the upper portion 35 of which the feeler stand may be secured by a bolt 25. At its front portion the feeler stand has a swivel block 26 through which the forwardly extending stem 27 of the feeler passes and a spring 28 interposed between the swivel block 26 and a collar or bridge 29 secured to the feeler and normally acting upon the feeler to move it rearwardly or to its feeling position. The parts so far described may be of usual construction and similar to the corresponding parts in the patent to Stimpson, hereinbefore mentioned.

The lay 30 is shown as of usual construction and provided with a shuttle box 31, the front wall of which is provided with an opening 32 which registers with an opening 33 in the front wall of the shuttle 34 when the latter is properly positioned in the shuttle box, so that on the beat-up movement of the lay, should the shuttle be in front position, the feeler may pass through the slots 32 and 33 and feel for the filling 35 in the shuttle. The part last described with respect to the lay and shuttle box may also be of usual construction.

The forwardly extending stem 27 of the feeler has a notched or toothed portion 36 which, when the feeler is in its inactive position, is engaged by a detent for maintaining the feeler out of cooperative rela-

tion with the filling. The detent as shown comprises an arm 37 pivotally mounted at 38 on the feeler stand and has a rearwardly extending portion 39 with a down-turned toe 40 laterally projecting at 41, Fig. 1. The detent is normally under the influence of a spring tending to move the forwardly extending arm 37 of the detent laterally into engagement with the stem of the feeler, and in the present instance the spring 42 is connected at one end at 43 with a pin projecting from the feeler stand and at its other end to a pin 44 on the detent.

The function of the detent is to hold the feeler in its forward non-cooperative relation with the filling during the periods of inactivity of the feeler and by pressing laterally upon the forwardly extending stem of the feeler to impart to the feeler a sufficient lateral movement to swing it about its bearing in the swivel block 26 and thereby carry the rear end portion of the feeler laterally into a position such that the feeler will not contact with the filling on detecting beats during its periods of inactivity. This position of the parts is indicated in Fig. 2 wherein the dotted line position of the feeler indicates its contacting and forward movement under the impulse of a working supply of filling in the shuttle, and its full line position shows the feeler in its inactive position swung laterally by the detent into non-contacting relation with the filling on subsequent detecting beats during its periods of inactivity.

To insure that the detent will not cause movement of the slide 20 to effect replenishment of filling, a limiting stop is provided which limits the lateral movement of the feeler when in its inactive position and under control of the detent. As indicated in Figs. 1 and 2, this stop is preferably formed as a projection 45 which, when the detent has been moved forwardly by a working supply of filling on a detecting beat and is thereupon engaged by the detent, will engage a wall 46 of the rear bearing or guide 22 and thus limit the lateral movement of the feeler under the lateral stress of the detent. Should the feeler, however, detect a near approach to exhaustion of filling in the shuttle on a detecting beat when the feeler is in its active position, it will not be moved forwardly sufficiently far to cause the detent to engage the toothed stem of the feeler nor will the projection or stop 45 be moved forwardly sufficiently far to engage the wall 46, with the result that the feeler is then free to function, to call for a change of filling, when substantial exhaustion of the filling is detected in the shuttle.

In accordance with the present invention, the feeler is to be held in forward inoperative relation with the filling by the

detent during its periods of inactivity and is to be freed from the detent at intervals to permit the feeler to move to feeling position, and in accordance with the present invention, this is effected through a trip device normally out of engaging relation with the cam follower or weft hammer and moved into cooperative relation therewith from time to time through a train of mechanism operated from a going part of the loom.

As shown in the present instance of the invention, the take-up or sand-roll 47 has its shaft 48 extended laterally and is provided with a rotary member or gear 49 which, of course, is given rotary movement by the take-up or sand-roll as the cloth is taken up during weaving, and such rotary member or gear 49 is provided with means for moving the trip device into cooperative relation with the cam follower or weft hammer from time to time, whereby the trip may be actuated by the weft hammer to effect release of the feeler from the detent.

In the present instance of the invention, the rotary member or gear 49 is provided with a series of teeth 50 which are engaged with the teeth 51 of a rotary member or gear 52 supported rearwardly thereof by a swinging arm 53 pivotally mounted at 54 on a bracket 55 which may be secured to the breast beam or shipper stand, as shown in Fig. 3, by means of suitable bolts 56. If desired, the bracket 55 may be adjusted towards and from the front of the loom by loosening the bolts 56 and moving it in the desired direction, such movement being permitted by the openings or slots 57 in the bracket. The support for the gear 52 here shown as constituted by the swinging arms 53 has a stop 58 which limits its movement by engagement with a portion of the bracket 55 and the arms 53, preferably two of them, between which the gear 52 is mounted, is normally under the influence of a spring 59, one end of which is secured to a stationary part, such, for instance, as a pin 60 projecting from the breast beam or shipper stand, and the other end of which is connected to a pin 61 on the swinging arms.

One of the gears 49 or 52 is provided with a tooth of less depth than the teeth of the respective gears, and in the present instance the gear 52 is shown as provided with such shallow tooth as at 62, which may be formed shallow by an integral portion of the tooth, as shown at the right, Fig. 3, or if desired, an adjusting screw 63 may be tapped into the space between two of the teeth and form the shallow portion therebetween. In either case, however, as the respective gears 49 and 52 are rotated during the take-up, the gear 52 will be moved rearwardly when the more shallow tooth thereof passes into

engagement with a tooth of the gear 49, the supporting arms 53 at such times swinging about their pivotal support 54.

Advantage is taken of the relative separating movements between the gears or rotary members 49, 52, described, to position the detent trip into cooperative relation with the cam follower or weft hammer. In the present instance of the invention the supports 53 carrying the gear 52 have a foot 64 extended rearwardly therefrom, and on such support 64 is mounted the trip 65 which, in the present instance, is shown as a lever pivoted at 66 upon the support 65 and extending in opposite directions therefrom, as indicated in Figs. 1 and 2.

When the support or the gear 52 is moved by the interengaging of the teeth of the gear 49 with the shallow tooth of the gear 52, the support 65 will be moved rearwardly to place the end portion 67 of the trip into the path of movement of the cam follower or weft hammer 10, with the result that on the next forward movement of the weft hammer, the trip 65 will be moved about its pivotal support to cause it to act upon the detent and trip the latter from engagement with the feeler so that the feeler may move to feeling position.

The trip 65 has a trip end portion 68 pivotally mounted at 69 on the end of the trip and normally under the influence of a spring 70, Fig. 1, and is free to swing against the tension of the spring in one direction but is prevented from swinging movement in the opposite direction by interengaging stops 71, Fig. 2, the construction being such that when the trip 65 is moved from its normal position, as indicated by full lines in Fig. 2, to exercise its tripping function, the pivoted trip 68 will engage the toe 41 of the detent and trip the feeler, but when the trip 65 is moved from its rearward or dotted line position, Fig. 2, into its front position, indicated by full lines, Fig. 2, the trip end 68 will ride over the end of the toe 41 of the detent and yield to permit the trip 65 to assume its initial position.

When the support 64 has moved the trip into its cooperative relation with the cam follower or weft hammer and the shallow tooth of the intermeshing gears has passed, the spring 59 will again move the support forwardly to carry the trip out of the path of movement of the weft hammer, and to insure at such time that the trip end 68 of the trip may pass forwardly of the detent toe 41, the arm 67 of the trip is provided with a bunter 72 which may be adjustably secured to the arm 67 as by a threaded end of the bunter and the holding nuts 73. The bunter 72 is positioned for engagement with the shaft 48 of the take-up or other part, so that when the support

64 on which the trip is pivoted is moved frontwardly, as described, from its active position, the bunter 72 will engage the fixed part or shaft 48 and cause the end trip 68 to move frontwardly into its position relative to the toe of the trip, as indicated in Fig. 2.

From the construction described, as indicating one form of the present invention, it will be noted that the feeler is held in a frontward non-cooperative relation with the filling during its periods of inactivity and is released at intervals to assume its feeling position by means of a trip which is given its tripping function by the cam follower or weft hammer and is normally out of the path of movement thereof, but is placed in the path of movement of the cam follower or weft hammer at intervals and is thereafter again moved to its inoperative position. While the present invention is shown as effecting such movement of the trip through a train of gears from the take-up, it is evident, of course, that the trip may be otherwise actuated within the scope of the present invention to move it bodily into and out of cooperative relation with a going part of the loom, and applicant believes himself to be the first in the art to provide a trip which is moved at intervals into the path of an actuator to effect release of the feeler and is then moved into an inoperative position with relation to the actuator to permit the feeler to be held in its frontward inactive position, and while the mechanism described is one embodiment of the invention in these respects, it is evident that such mechanism may be varied within the true scope of the present invention as defined by the claims.

The cam follower or weft hammer 10 is mounted, as usual, to rock upon a support 74, Fig. 1, and its rearwardly extending arm 75 has a shoe 76 which rides upon a cam 77 on a cam shaft 78 to impart to the cam follower or weft hammer its usual movement towards and from the front of the loom.

What is claimed is:

1. In a loom, the combination of a feeler to detect the condition of the filling in the shuttle, a device for holding the feeler in an inoperative position, means for freeing the feeler from said device at intervals, a cam follower, and mechanism for placing the feeler freeing means in operative relation with the cam follower at intervals that the feeler may have periods of activity and inactivity during weaving with the same supply of filling in the shuttle.

2. In a loom, the combination of a feeler, a device for holding the feeler out of cooperation with the filling, a normally inoperatively positioned trip for freeing the feeler from said device, and means for moving the trip periodically into operative relation with

a going part of the loom that it may be actuated to free the feeler.

3. In a loom, the combination of a feeler, a device for holding the feeler out of cooperative relation with the filling, and means periodically moved into a position for actuation by the cam follower to free the feeler from the holding device.

4. In a loom, the combination of a feeler, a device for holding the feeler out of cooperative relation with the filling, a trip for said device, a movable support for the trip, and means acting periodically for moving the trip support to place the trip in operative relation with a going part of the loom.

5. In a loom, the combination of a feeler, means for holding the feeler from cooperative relation with the filling, a device for freeing the feeler from said means, a cam follower normally out of cooperative relation with said device, and means for relatively moving said device and cam follower into cooperative relation to free the feeler from said holding means at intervals.

6. In a loom, the combination of a feeler, means for holding the feeler from cooperative relation with the filling, a device for freeing the feeler from said means, a cam follower normally out of cooperative relation with said device, a movable support for said device, and means for moving the support periodically to place said device in position to be actuated by the cam follower.

7. In a loom, the combination of a feeler, means for holding the feeler in a retracted frontward position, a trip for freeing the feeler from said means, an actuator for the trip with relation to which the trip normally occupies an inoperative position, and means for periodically moving the trip into the range of movement of the actuator to free the feeler at intervals that it may have active and inactive periods during weaving.

8. In a loom, the combination of a feeler, means for holding the feeler in frontward retracted position, a trip supported back of the shipper stand, a trip actuating member with relation to which the trip is normally inoperatively positioned, and means for moving the trip periodically into operative relation with the actuating member that it may release the feeler from the holding means periodically.

9. In a loom, the combination of a feeler, means for holding the feeler in a frontward retracted position, a trip supported between the lay and shipper stand for freeing the feeler from the holding means, a cam follower, and means for periodically placing the trip and cam follower in operative relation that the feeler may have periods of activity and inactivity during weaving.

10. In a loom, the combination of a feeler, means for holding the feeler in a frontward position, a trip for freeing the feeler from

said means, an actuator for the trip, and means operated from the take-up for placing the trip and trip actuator in operative relation at intervals.

6 11. In a loom, the combination of a feeler, means for holding the feeler in a frontward position, a trip for freeing the feeler, an actuator for the trip, and means for bodily moving the trip to and from operative relation with the actuator at intervals during weaving.

12. In a loom, the combination of a feeler, means for holding the feeler in a frontward position, a trip for freeing the feeler, a 13 cam follower, and means for moving the trip into the path of the cam follower at intervals.

13. In a loom, the combination of a feeler, means for holding the feeler in a frontward 20 position, a trip for freeing the feeler, a cam follower, and means operated from the take-up for moving the trip into the path of the cam follower at intervals.

14. In a loom, the combination of a feeler, 25 means for holding the feeler in a frontward position, a trip for freeing the feeler at intervals, a support for the trip, a cam follower, and means for moving the trip support at intervals to place the trip in position to be actuated by the cam follower.

15. In a loom, the combination of a cam 30 follower, a feeler, means for holding the feeler in a frontward retracted position, a trip for freeing the feeler, a support for the trip at the rear of the shipper stand normally supporting the trip in an inoperative position, a cam follower, and means active at intervals to move the trip support and place the trip in the path of movement 40 of the cam follower.

16. In a loom, the combination of the cam follower, a feeler, means for holding the

feeler in a frontward position, a trip, a support for the trip, and means for moving the trip support towards and from the rear of the loom at intervals to place the trip in position to be actuated by the cam follower from time to time that the feeler may have periods of activity and inactivity during weaving.

17. In a loom, the combination of a feeler, means for holding it in a frontward position, a trip for freeing the feeler, a trip support, a rotary element connected to the take-up having a part to move the trip support 55 at intervals and operatively position the trip, and an actuator for operating the trip when in its operative position to free the feeler from the holding means.

18. In a loom, the combination of a cam 60 follower, a feeler mounted for movement in a direction longitudinally of the shuttle, means acting laterally upon the front end portion of the feeler to move the rear end of the feeler laterally beyond the reach of the filling, and a trip actuated at intervals by the cam follower to free the feeler from the holding means.

19. In a loom, the combination of a feeler 70 mounted for movement in a direction longitudinally of the shuttle, a detent acting laterally upon the front end portion of the feeler to move the rear end laterally beyond the reach of the filling, a projection on the rear end of the feeler to engage a part connected to the feeler stand to limit the lateral movement of the feeler under the action of the detent and thereby prevent premature replenishment of filling by the action of the detent on the feeler, and a trip for freeing 80 the feeler from the detent at intervals.

In testimony whereof, I have signed my name to this specification.

ISAAC SNOW.
